UNITED STATES PATENT OFFICE.

CHARLES B. HUGHES, OF NEW ORLEANS, LOUISIANA.

TENSION DEVICE FOR USE IN ORTHOPEDIC SURGERY.

1,380,297.

Specification of Letters Patent. Patented May 31, 1921.

Application filed October 5, 1920. Serial No. 414,732.

To all whom it may concern:

Be it known that I, CHARLES B. HUGHES, a citizen of the United States, residing at New Orleans, in the parish of Orleans and 55 State of Louisiana, have invented new and useful Improvements in Tension Devices for Use in Orthopedic Surgery, of which the following is a specification.

The object of this invention is to provide 10 a tension device which shall take the place of the usual gravity pull used in cases involving orthopedic surgery and fractures of the limbs where a steady pull is required during treatment.

15 A further object is to provide means for varying the pull or tension by providing springs of different capacities, so that the surgeon may be able to obtain the exact pull desired, and by providing a scale member 20 on which the pull shall be registered in pounds.

A still further object is to provide a device of the type indicated, to be attached to the head or to the foot of a bedstead, and 25 to include an arm to be clamped in position, an arm resiliently mounted with reference to the arm first named, and means for mounting a spring or a plurality of springs between the arms for normally holding 30 them separated,—a flexible device connecting the resiliently mounted arms with the elements usually attached to the foot of a patient, in the case of fracture of the limb, so that a steady pull may be exerted.

35 Another object is to provide means for sounding an alarm in case the movable and resiliently mounted arm is brought into contact with the stationary arm, the nurse and patient being thereby notified, so that the 40 proper steps may be taken for placing the apparatus in position for further and continued operation.

With the foregoing and other objects in view, the invention consists in the novel construction, combination, and arrangement of 45 elements hereinafter described and claimed.

In the drawings, Figure 1 is a view of the device in side elevation; Fig. 2 is a top plan view; Fig. 3 is an elevation, looking from 50 the right in Fig. 1; Fig. 4 is an elevation, looking from the left in Fig. 1.

In carrying out my invention I provide

an arm 10 provided with a longitudinal slot 11 and having a pulley 12 mounted near one end of the arm, and preferably mounted in the slot just mentioned.

A movable arm 14 is resiliently mounted with reference to the arm first named, and may be conveniently connected with one end thereof by means of a spring hinge 15. 60 Springs 16 and 17 of the form shown may also be connected with the outer edge portions of the arms, for the purpose of retaining them normally separated. The arm 10 is secured to the bedstead by means of 65 the clamping elements 18 and 19.

Extending transversely of the arm 10 is a bar 20 having mounted thereon a rod 21 which serves to support a swinging U-shaped frame 22, the central portion of which 70 serves to mount a sleeve 23 bearing directly against the plate or plates 24 on the inner side of the movable arm. Springs 26, 27 and 28 encircle rod 21, one end of each spring being rigidly connected with the bar 75 and the other end bearing against a portion of the U frame 22 for exerting pressure upon the latter and forcing the sleeve just referred to into contact with the movable arm. The bar mounting the springs is slid- 80 able with reference to the stationary arm, as stated, being secured by a bolt 29 and a wing nut 30. The opposite sides of the stationary arm may carry plates 31 and 32, permitting the sliding movement and prevent- 85 ing unnecessary wear on the stationary arm.

The flexible device 34, such as a cord, adapted for connection with the elements secured to the foot of the patient, or other portion of the body, passes first over the 95 pulley 12, and then through the movable arm, a sleeve 36 being provided if desired. The cord is then connected with the ring member 38 of a spring scale of the usual commercial type and shown at 40, the opposite end of the scale being connected with the movable arm at a point 41. A retaining arm or loop 42 is connected with the stationary arm and passes around the movable arm, and limits the outward movement 100 thereof.

In order to notify the nurse and patient in the event that the movable arm contacts with the stationary arm, I provide a contact

making device 45 which serves to complete the circuit through an electric buzzer 46, for the purpose indicated, a battery being shown conveniently at 48, and the wires of the circuit are designated 49 and 50.

There are a number of decided advantages in connection with the use of the device, over the well known gravity operated apparatus. In the latter the weights come in contact with the floor, at times, and are unnecessarily heavy, it being practicable to produce the same pull, in pounds, by the use of springs of very light weight. The bar carrying the springs is easily detached, and in order to vary the pull, it is only necessary to substitute another bar carrying springs formed of wire of a different gage. In the manufacture of the apparatus, it is obvious that details of construction may be varied within the scope of the appended claims.

What I claim is:—

1. In a device of the class described, an arm to be mounted in a fixed position, an arm mounted to swing with reference thereto, a spring for resisting the action of such movement, and a flexible device for moving the second named arm against the action of the spring.

2. In a device of the class described, an arm adapted to be mounted in a fixed position, an arm mounted to swing with reference to the arm first named, a spring for retaining the arms normally separated, means for detachably mounting the spring, and a flexible device connected with the second named arm for moving said arm against the tension of the spring.

3. In a device of the class described, a swingingly mounted arm, a spring for resisting the movement of the arm, flexible

means for moving said arm against the tension of the spring and an alarm acting as a warning when the arm moves to position rendering the spring inactive for producing tension on the flexible means.

45

4. In a device of the class described, a plurality of arms having hinged connection, a spring for normally holding the arms separated, a spring scale for registering the pull in pounds necessary to move one arm 50 toward the other against the tension of the spring, and means for connecting the scale member with an object upon which the tension is to be exerted.

5. In a device of the class described, an arm, a pulley mounted near one end thereof, an adjustable clamp for connecting the arm with a stationary object, a movable arm hinged to the arm first named, a detachably mounted spring element connected with the 60 arm first named and adapted to press against the second named arm, a flexible element for moving the second named arm against the tension of the spring.

6. In a device of the class described, an arm, a pulley mounted near one end thereof, an adjustable clamp for connecting the arm with a stationary object, a movable arm hinged to the arm first named, a detachably mounted spring element connected with the 70 arm first named and adapted to press against the second named arm, a flexible element for moving the second named arm against the tension of the spring and a scale member for registering the pull in pounds and having 75 connection with the flexible element and with the second named arm.

In testimony whereof I affix my signature.

CHARLES B. HUGHES.
